UNITED STATES PATENT OFFICE.

CHARLES T. SCHOEN, OF PHILADELPHIA, PENNSYLVANIA.

DRAW-BAR-SPRING POCKET.

SPECIFICATION forming part of Letters Patent No. 426,143, dated April 22, 1890.

Application filed March 3, 1890. Serial No. 342,385. (No model.)

To all whom it may concern:

Be it known that I, CHARLES T. SCHOEN, a citizen of the United States, residing at Philadelphia, in the county of Philadelphia and State of Pennsylvania, have invented a certain new and useful Improvement in Draw-Bar-Spring Pockets, of which the following is a full, clear, and exact description.

The object of this invention is to simplify and cheapen the construction of the pockets for the draw-bar springs of railway-car couplings. In the master car-builder's standard pocket there are some forty-eight bolts, straps, and castings, which render the device costly, complex, and unduly increase the dead-weight of the car, aside from the consideration of expense in time and labor in assembling. The use of pressed steel in making railway-car fittings, as illustrated in several patented inventions of mine which have gone largely into use, the increased serviceableness of such fittings, their great durability and lightness, coupled with their faculty of interchangeability with the cast-metal fittings which they supersede, demonstrate the feasibility of the more extended use of this form of metal, and have led up to the present invention. It is proper to say here, however, that, broadly speaking, pressed-steel angle beams or plates have been applied to the draft-rigging in substitution of the ordinary oak draft-timbers, and also that pressed-steel pockets have been devised; but these render necessary a reorganization of the draft-rigging, and this I purpose wholly to avoid.

The invention consists, then, in draw-bar guide-plates for the pockets of railway draw-bar springs constructed of pressed steel or other wrought metal, and so as to be interchangeable with the standards in common use, substantially in the manner hereinafter more particularly set forth and finally claimed.

In the accompanying drawings, illustrating my invention, in the several figures of which like parts are similarly designated, Figure 1 is a bottom plan view; Fig. 2, a vertical sectional elevation, its plane being in the line xx of Fig. 1; and Fig. 3 is a vertical cross-sectional elevation of the ordinary master car-builders' standard arrangement of the draw-bar timbers and spring-pocket, showing my

guide-plates substituted for those of the master car-builder's standard. Fig. 4 is a perspective view of the guide-plate detached.

The longitudinal timbers a and cross-timbers b , the springs c , and follower-plates d may be as usual.

In order to construct the guide-plates of pressed steel or the like so as exactly to replace or interchange with those used in the master car-builder's standard, and to adapt them to be applied without new bolts and new bolt-holes, I make each of the pairs of guide-plates entering into the construction of a draw-bar-spring pocket of a single piece of plate-steel or equivalent wrought metal, as shown in detail especially in Fig. 4—that is to say, I take a piece or blank of the selected material, and by means of dies or other suitable tools, I form the cavity e , the bottom of which is to rest upon the timbers a , and this cavity terminates in shoulders f , against which the follower-plates d abut and form the draw-bar stops, and then the ends g of the plate return to the plane of the bottom of the cavity and terminate in flanges h , which are to be let into kerfs or grooves in the timbers a . The ends g receive the usual bolts i for securing the plates to the timbers. A rib j is projected from the bottom of the cavity, and it also is let into the timbers a . Flanges k extend the length of the longitudinal edges of the plate, and are made integral therewith. Thus the guide-plate is complete in one piece.

The configuration and size of the plate may be varied as may be required, and so, also, may be its mere details of structure. The flanges, ribs, and shoulders also serve to add strength and stiffness to the plate.

I prefer to make countersinks l in the ends g to receive the heads of the bolts i .

A guide-plate constructed in accordance with the principle of my invention is interchangeable as to size, bolt-holes, centers, &c., with present standards. Moreover it reduces the number of parts comprising a draw-bar-spring pocket from forty-eight in the present standard to twenty in mine. It is also very much stronger, more durable, less liable to displacement, and quite as cheap, if not cheaper.

What I claim is—
1. As an improved article of manufacture,

a guide-plate for draw-bar-spring pockets constructed for interchange with the castings and other parts forming the master car-builder's standard and other common standards, and 5 to be applied in the ordinary draft-rigging, and comprising, essentially, a shouldered cavity to receive the ordinary spring follower-plates, bolt-holes to receive the ordinary bolts in the draft-timbers and longitudinal edge 10 flanges, and struck up in a single piece from plate steel or like metal, substantially as described.

2. A guide-plate for draw-bar-spring pockets, constructed of wrought metal, preferably 15 steel-plate, die-shaped, and having a shouldered cavity to receive the spring follower-plates, and ends provided with bolt-holes and edge flanges, substantially as described.

3. A guide-plate for draw-bar-spring pockets, constructed of wrought metal, preferably 20 steel plate, die-shaped, and having a shouldered cavity to receive the spring follower-plates, ends provided with bolt-holes and terminating in transverse flanges, and flanges

along the longitudinal edges, substantially as 25 described.

4. A guide-plate for draw-bar-spring pockets, constructed of wrought metal, preferably 30 steel plate, die-shaped, and having a shouldered cavity to receive the spring follower-plates, a transverse rib at the bottom of the cavity, and ends provided with bolt-holes and longitudinal edge flanges, substantially as described.

5. A guide-plate for draw-bar-spring pockets, constructed of wrought metal, preferably 35 steel plate, die-shaped, and having a shouldered cavity to receive the spring follower-plates, a transverse rib at the bottom of the cavity, ends provided with bolt-holes, transverse 40 end flanges, and longitudinal edge flanges, substantially as described.

In testimony whereof I have hereunto set my hand this 1st day of March, A. D. 1890.

CHARLES T. SCHOEN.
